PERCUSSIVE TOOL

Filed May 2, 1927

FIG-1

INVENTOR.
Fred M. Slater
BY *Reinbold & Clegg*
HIS ATTORNEY

UNITED STATES PATENT OFFICE.

FRED M. SLATER, OF EASTON, PENNSYLVANIA, ASSIGNOR TO INGERSOLL-RAND COMPANY, OF JERSEY CITY, NEW JERSEY, A CORPORATION OF NEW JERSEY.

PERCUSSIVE TOOL.

Application filed May 2, 1927. Serial No. 188,202.

This invention relates to fluid actuated percussive tools, but more particularly to throttle valves and their controlling means for tools of this type.

5 The objects of the invention are to simplify and lighten the construction of tools of this type and to enable the admission of pressure fluid into the tool to be controlled by pressure ordinarily applied to the handle for holding 10 the said tool to the work.

Other objects will appear hereinafter and to all of these ends the invention consists of the combination of elements and arrangement of parts having the general mode of operation 15 substantially as hereinafter described and claimed and illustrated in the accompanying drawings, in which

Figure 1 is a sectional elevation of so much 20 of a percussive tool as will serve to illustrate the invention, and

Figure 2 is a side elevation of the handle.

Referring to the drawings, the invention is shown embodied in a percussive tool of the coal pick type having a barrel A in which 25 is disposed a reciprocating hammer piston B for delivering blows on a working implement (not shown).

On the rearward end of the barrel A is screwed a handle C in the front end of the 30 body portion D of which is formed a recess E consisting of an outer threaded portion F for engagement with threads G on the end of the barrel A and a rearward smooth annular portion which serves as a valve chest H. The 35 body portion D thus acts as a back head for the barrel A and also serves to clamp a valve seat J located in the valve chamber H against the rearward end of the barrel A.

The rearward end of the valve seat J has 40 two converging surfaces K on which is disposed a distributing valve L of the oscillatory flat plate type pivoted on a pin O anchored in the valve seat J. Inlet passages P and Q leading to the rearward and front ends respectively of the barrel are formed in the seat J and are controlled by the valve L.

Pressure fluid for actuating the tool may 45 be conveyed from a suitable source of supply (not shown) into a connection R which communicates at its inner end with a throttle valve chamber S formed in one side of the body portion D. The valve chamber S preferably lies in a plane paralleling the longitudinal axis of the tool and its rearward portion T is in this instance reduced somewhat

50 to form a valve seat U on which is seated a spring pressed throttle valve V. The throttle valve controls the admission of pressure fluid from the valve chamber S into the reduced portion T from whence it may flow into the valve chest H through a passage W which affords communication between the reduced portion T of the valve chamber and the valve chest H.

In the present instance the throttle valve V 55 is provided with a stem X guided by a rearwardly extending projection Y on the body portion D and extending with its free end beyond the rearward end of the said projection Y.

60 In accordance with the invention, means are provided for unseating the throttle valve V and also for guiding the tool with respect to the work. To this end a handle grip Z is pivoted on a pin Z' extending through lugs 65 b on one side of the body portion D and the opposite or free end of the handle grip Z terminates at a point in line with the projection Y wherewith it is in slidably engagement by means of a pair of downwardly extending 70 walls c which form a slot d into which the end of the projection Y extends for holding the free end of the handle grip against lateral movement with respect to the body portion. Preferably a removable wearing piece e is inserted in the handle grip Z to protect the handle grip Z against such wear as is usually 75 caused by the stem X.

80 In order that the handle grip Z may be held against too free movement about its pivotal point, the said handle grip Z is provided with a surface f near its pivotal point to abut a surface g on the side of the body portion D. These surfaces f and g are so located that 85 when the throttle valve is closed only a slight 90 space may exist between the rearward end of the stem X and the wearing piece e.

95 The present invention has been found to be particularly desirable for use in connection with percussive tools of the coal pick type 100 or other similar tools in which the tools are not only used for drilling purposes but also for prying the material after the hole has been drilled. The present invention enables all the relatively movable and interlocking 105 portions of the body portion and the handle grip to be of rugged construction, capable of withstanding the most severe usage and, this, without materially increasing the weight of the tool.

I claim:

A fluid actuated percussive tool, comprising a barrel, a reciprocating piston, a distributing valve at the rearward end of the barrel, 5 a handle secured to the barrel, said handle having a body portion forming the back head of the tool, a projection on the body portion extending rearwardly of said body portion, a spring pressed throttle valve in the body portion 10 having a stem extending slidably through the projection and adapted to project from the rearward end of the projection, a handle grip for the tool secured to and pivoted on only one end of the body portion and

adapted to be pressed with its free end 15 against the stem for opening the throttle valve, a slot in the free end of the handle grip to engage the projection for holding the handle grip against lateral movement with respect to the body portion, and cooperating 20 surfaces on the handle grip and the body portion adjacent the pivotal point of the handle grip for limiting movement of the handle grip with respect to the projection.

In testimony whereof I have signed this 25 specification.

FRED M. SLATER.
